UNITED STATES PATENT OFFICE.

ALBERT G. SCHERER, OF CHICAGO, ILLINOIS, ASSIGNOR TO EXCELSIOR STEEL FURNACE COMPANY, OF CHICAGO, ILLINOIS, A CORPORATION OF ILLINOIS.

PIPE CONNECTION OR BOOT.

Application filed June 21, 1922. Serial No. 569,859.

To all whom it may concern:

Be it known that I, ALBERT G. SCHERER, a citizen of the United States, residing at Chicago, in the county of Cook and State of

5 Illinois, have invented a new and useful Improvement in a Pipe Connection or Boot, of which the following is a specification.

My present invention has relation to improvements in double-wall boots for double-wall hot air duct or stack. Hot air duct or stack is employed in the heating and ventilating art to provide conduit between the joists in the floors and between studding in the walls of buildings to convey the air to 10 the portion of the building into which it is desired to discharge it or from which it is desired to draw it, and to permit of the greatest capacity of this duct under these conditions it is made of rectangular cross-20 section so as to fit between the joists and the studding. The connection between the lowermost portion of the rectangular section system and the furnaces, or means for withdrawing the air, is made through what is 25 technically known as a "boot," one end whereof is designed for assembly with the duct of rectangular section, while the other end of the boot is provided with a collar adapted to assemble with a round pipe running to the furnace for heating or for exhausting the air.

Especially in the conduction of heater air it has been found the better practice to make the duct of two walls spaced from each other 35 so as to provide around the inner hot air carrying wall an air insulation which prevents the loss of heat during the passage of the air, and also prevents conduction of heat to the joists and studding between 40 which the duct is installed and thereby eliminates a fire hazard. It is also the better practice to make the boot with double walls.

When double-wall boots were first made it was the usual practice to make both the 45 inner and outer walls of the same with angular edges and with flat or plane walls. Later boots were designed in which the walls were tapered from the round collar with which the round pipe assembled to the angular end which assembled with the stack. The angular form of boot had the advantages of strength and economy in manufacture, and the tapered form of boot, especially with reference to the interior wall, 50 had the advantage of offering less friction

to the conducted air as there were no corners present which would permit of the formation of eddies, and thereby impede the flow of the air.

My present invention consists in providing a double-wall boot with a tapered interior wall and flat angular exterior walls, and the advantages of this structure over the prior structures are that while I retain the advantage of the tapered structure in so far as conduction is concerned, I have increased the insulating space around the inner wall; I have greatly increased the strength of the structure by combining the tapered with the angular flat walls, and I have also effected a material economy in the manufacturing cost of the article. I attain the aforementioned objects and results by means of the structure illustrated in the accompanying drawings, in which—

Fig. 1 is a perspective of a boot embodying my invention showing its assembly with fragments of rectangular and cylindrical sections of pipe.

Fig. 2 is a central vertical section thereof.

Fig. 3 is a side elevation of the boot detached from the stack, a portion of the adjacent outer wall being broken away to disclose the interior arrangement.

Fig. 4 is a fragmental top plan of the upper portion of the boot.

Fig. 5 is a horizontal section taken on line 5—5, Fig. 1.

Fig. 6 is a horizontal section on line 6—6, Fig. 1.

The interior walls of my improved boot are formed of what may conveniently be regarded as a rear piece or section 7 and front piece or section 8 which are developed upon well known geometrical principles so that when their longitudinal edges are secured together, preferably by double seaming, as at 9, one end will be of circular form, and the top end with bends 10, 10, provided adjacent the upper edges of sections 7 and 8 will be of rectangular cross-section. To the round end of sections 7 and 8 is secured by seaming, in this case technically known as "peaning," a circular element or collar 11, the ends whereof are secured by rivets 12, or in any other suitable way, and the lower edges whereof, both for stiffness and finish, is rolled, as at 13. In order to facilitate the adjustment of the rectangular end to proper dimensions the corners of the portion of the

boot of rectangular cross-section are cut back to permit of adjustment in the final operations of manufacture.

About collar 11 and close against the connection with sections 7 and 8 is disposed a sheet of metal 14 of rectangular form the center whereof has been cut away so as to permit the collar to extend therethrough. To the rear edge of this sheet 14 is seamed 10 a back 15 extending upwardly at right angles with sheet 14, and to the sides of sheet 14 are seamed the sides 16 of the outer wall of the boot which are also seamed to the back wall and have their front edges 15 inclined in a plane extending from a point above the front edge of sheet 14 to a point just in front and below the upper angular portion of the front inner wall. To the front edge of sheet 14 and the front edges 20 of the sides is seamed the front outer wall 17. The rear, sides and front outer walls are then formed with shoulders 18 and carried still higher and then bent downwardly and inwardly, as at 19, to contact with the 25 rectangular portions of the inner walls. These walls are then carried upwardly and over the upper edges of the angular portions of the inner walls to which they are suitably secured. I have illustrated the 30 securing of the top of the outer walls and included inner wall with diagonal crimping 20. It will also be seen that I have illustrated the formation in the outer walls of the locking bead 21 illustrated in my previous Patent No. 1,085,303 of January 27, 1914.

The edges of the outer walls forming the corners of the portions which are adapted to assemble with the portion of the inner 40 pipe of rectangular section are cut away, as at 22, and to close the cut away portions in both the inner and outer walls, I insert between the inner and outer walls corner pieces 23 which are secured in place by the diagonal crimping which also secures the outer and inner walls together. I have also illustrated in the outer side walls 16 punched out straps 24 which are adapted to receive strips of metal to be nailed to the adjacent joists or studding, but this detail forms no portion of my present invention, although boots with tapered exterior walls could not employ this feature with the same facility.

It will now be seen from the foregoing 55 discussion and description, taken in connection with the drawings, that I have provided a boot which is in no way inferior to the tapered boot in conductivity of air, 60 but which is stronger, cheaper to make and

provides increased insulation against the escape of heat over either style of boot heretofore upon the market.

What I claim is:

1. A double wall boot for hot air duct 65 having an annular collar, an inner wall tapering from said collar to an opposite end of rectangular section, and an outer casing of flat walls through an end wall of which said collar extends, the side walls of 70 said outer casing adjacent the rectangular portion of the interior structure being formed with shoulders and united with the walls of the interior structure.

2. A boot for air duct comprising two 75 tapering walls, one of said walls being of rectangular cross-section throughout, and the other of said walls being cylindrical at one end and merging into the rectangular shape of the other wall at its opposite end. 80

3. A double-wall boot for air duct comprising an outer wall of rectangular cross-section throughout and tapered towards its top, and an inner wall of cylindrical cross-section at its lower end and tapered up- 85 wardly and merging into a rectangular cross-section at its upper end parallel with the adjacent portion of said outer wall.

4. A boot for air duct comprising a cylindrical collar, an inner wall connected at its lower end to said collar and tapered toward its opposite end to a rectangular cross-section, an outer wall spaced from said inner wall; said outer wall being of rectangular cross-section throughout and ta- 90 pered towards its upper end, a transverse plate extending around the cylindrical portion of said structure and connected at its outer edges to said outer wall, and said inner and outer walls shaped to each other 95 and crimped together at their upper ends.

5. A double-wall boot for air duct comprising an outer wall of rectangular cross-section throughout, an inner wall of cylindrical cross-section at its lower end and merged into a rectangular cross-section at its upper end; said inner and outer walls spaced apart and tapered upwardly and secured together at their upper ends, a cylindrical collar secured to the lower end 105 of said inner wall, and a closure plate ex- 110 tending laterally from said collar and having its outer edges secured to the lower edges of the outer walls.

Signed at Chicago, county of Cook and 115 State of Illinois, this 13th day of June, 1922.

ALBERT G. SCHERER.

Witness:

FLORENCE MITCHELL.
